BURNER ATTACHMENT

Frederick C. Lahn, Brooklyn, N. Y., assignor of
ten per cent to Percy W. Valentine and five
per cent to Pasquale Leanza, Brooklyn, N. Y.

Application March 30, 1935, Serial No. 13,877

17 Claims. (Cl. 158—113)

This invention relates to burner attachments and particularly to devices of this class adapted for use in connection with kerosene and other fuel oil burners; and the object of the invention is to provide a device designed to control and regulate the flame of the burner and to improve its combustion characteristics to provide a more efficient operation of the burner for the several purposes for which it is intended, and especially in the use of one or more burners of the kind under consideration in a stove or range to more efficiently and economically heat the oven, stove top or vessels placed thereon as well as the water jacket of the stove for heating a water supply system; a further object being to provide an attachment of the class described in the form of an elongated sheet metal body having a central flue portion and diverging wings to control and regulate the flame or products of combustion rising from the burner and to direct it to surrounding walls of a stove or range to produce the most efficient results; a further object being to provide an attachment of the character described including adjustable parts or sections by means of which the same may be adapted to ranges or stoves of various kinds and types; and with these and other objects in view, the invention consists in an attachment of the class and for the purpose specified which is simple in construction, efficient in use and which is constructed as hereinafter described and claimed.

The invention is fully disclosed in the following specification of which the accompanying drawing forms a part, in which the separate parts of my improvement are designated by suitable reference characters in each of the views, and in which:

Fig. 1 is a diagrammatic sectional view of a part of a stove and burner indicating one form of my attachment in connection therewith.

Fig. 2 is a sectional view through the stove shown in Fig. 1 illustrating two burners and the attachment in elevation.

Fig. 3 is a sectional detail on the line 3—3 of Fig. 1.

Fig. 4 is an end and sectional view of a modified form of attachment which I employ; and,

Fig. 5 is a plan view of the structure shown in Fig. 4.

In Figs. 1 and 2 of the drawing I have shown for the purpose of illustrating one method of carrying my invention into effect a cooking stove 10 having a baking oven, part of which is indicated at 11, a water jacket as indicated at 12, a top plate 13 having removable covers 13a, and

a fire box or heating chamber 14 arranged between the water jacket 12 and the oven 11. At 15, I have indicated a part of the flue passage to a chimney or outlet through which the products of combustion from the fire box 14 are adapted to pass. At 16, 16a, I have indicated two kerosene oil burners arranged in the fire box 14. These burners may be arranged in a conventional coal or wood stove or in a stove constructed for the use of such burners. At this time, it will also be apparent that my improved attachments are adapted for use in connection with burners of various kinds and classes and for various uses.

In the construction shown in Figs. 1, 2 and 3, I have shown an attachment 17 made substantially from a single sheet of suitable material and this type of an attachment is adapted for use in conjunction with different factory-built burner units, whereas the attachments shown in Figs. 4 and 5 of the drawing are adapted to be sold on the retail market and are adaptable for use in conjunction with various types and kinds of burners.

The attachment 17 is formed from an elongated sheet of material, sheet metal being shown in the accompanying drawing. This sheet is fashioned to form a longitudinal flue passage 18 substantially of the cross sectional contour illustrated in Fig. 1 of the drawing, and bounded by a straight side wall 19 and an opposed wall 20 which for a portion of its width is parallel to the wall 19 and terminates at its upper end in inwardly curved flanges 21 arranged at the ends of the sheet as may be seen in Fig. 2 of the drawing and a bottom, outwardly beveled wall 22 forming a wide throat or admission opening 18a for the flue passage 18. The purpose of this wide throat construction is to create a force draft through the flue 18 and at the same time pull the flame or products of combustion from the side of the 40 burner adjacent the oven 11 to direct it to the top of the stove and thus through the flue passage 15 so as to provide more effective heating of the top plate 13 or the covers 13a thereof which are disposed above the burners 16, 16a or to cooking 45 pots, pans or vessels arranged thereabove.

At the lower end of the wall 19, the sheet is folded upon itself to form a downwardly directed longitudinal beveled strip or flange 23 which also forms a supporting leg for the attachment. The 50 side portion 24 of the sheet extends upwardly and outwardly from the flange 23 forming a deflector or baffle plate to direct the flame or products of combustion rising from the burners 16, 16a to the water jacket 12.

The other side portion 25 of the sheet is folded to form an upwardly and outwardly extending deflector or baffle, the intersecting corner between the portions 22 and 25 being disposed above the lower edge of the flange 23 to form a clearance space longitudinally of the attachment whereby the flame or products of combustion from adjacent sides of the burners may be drawn into the flue 18 through the throat 18a. The end portions of this side of the attachment are supported above the burners by offset brackets or foot members 26 welded or otherwise secured to the part 22 as clearly indicated in Figs. 1 and 2 of the drawing.

The upper free edges of the baffles 24 and 25 are provided with outwardly pressed beads 24a, 25a respectively which form steps adapted to engage opposed side walls of the fire box 14 to provide passages 27 and 28 for the products of combustion from the fire box 14 upwardly to the top of the stove and through the flue passage 15. The walls 19 and 20 are spaced apart by a central deflector hood 29 which extends in an upward and forward direction in the fire box 14.

The burner 16 is disposed at the front of the fire box and the head 29 is adapted to draw some of the products of combustion from the burner 16a and direct the same forwardly to keep the heat to the front of the stove as much as possible and to counteract the natural draft which extends from the front of the fire box backwardly through the stove. The burners 16, 16a are of a conventional type employing a plurality of cylinders 30, 30a, 30b and 30c having perforated walls and arranged in an outer casing 31. At 32 and 33 I have indicated the burner or flame passages of the two burner wicks which are employed in burners of the class under consideration. At 34 I have shown the usual top plate controlling the passage of the flame through the burner. Upon this plate my improved attachment is supported.

In the use of my improved attachment, a large part of the flame and in fact, the major part of the flame rising from the burners at the oven side thereof is drawn upwardly through the flue 18 and a part thereof including the normal radiation of heat from the burner will be directed toward the oven and out through the discharge 28 as indicated by the arrows in Fig. 1 of the drawing. At the same time, the baffle 23 serves to confine the flame and heat rising from the other side of the burners in the direction of the water jacket 12 for discharge through the passage 27. The flame and products of combustion rising through the flue 18 are also extended in a forward direction by virtue of the inturned flanges 21, thus preventing a direct discharge of the flame and products of combustion into the flue passage or heating chamber 15. The flame and products of combustion will travel to both sides of the upturned flange 21 and this is encouraged centrally of the attachment by virtue of the forwardly extending hood 29 which also draws the flame and products of combustion from the burner 16a in the direction of the burner 16.

With my improved attachment, I have found from experimentation and experience that more efficient heating of the oven, water jacket as well as stove top may be accomplished at the least amount of fuel consumption. My attachment serves to harness or retard the products of combustion within the area of the stove. At the same time, I have found a better flame will rise from the burners and will spread over a greater area

of the fire box 14, stove top 13 and throughout the heating chamber or flue 15. The baffles 24 and 25 will spread the flame or products of combustion a greater degree within the fire box and restrict the discharge therefrom through the passages 27 and 28 disposed adjacent the walls 5 of the fire box to be heated.

With oil burners of the class under consideration, it has long been experienced that quick and effective heating of an oven or the cooking of 10 food products disposed above the burners has been impossible, and a great delay in time has been experienced to successfully perform the cooking or baking operations desired at a great amount of fuel consumption. Further, it has 15 been found difficult if not impossible to maintain proper temperature of the water in the water jacket, especially when the stove is being used for other purposes.

With my improved attachment, however, I 20 have found that I can cook and bake substantially as quickly as these operations can be performed with a conventional gas stove or range, and at all times the water in the water jacket will be maintained at the proper or desired temperature. When the stove is being utilized solely for heat radiation purposes and the heating of water, the burner or burners may be turned down and operated at a very nominal fuel consumption. In addition to added efficiency and 30 utility, I also have effected a decided economy in the burner operation and still further have saved considerable time heretofore lost in performing the cooking and baking operations.

In the construction shown in Figs. 4 and 5 of 35 the drawing, I have illustrated an attachment which is substantially identical in general form to the attachment 17 shown in Figs. 1 and 2 with the exception that the side portions are composed of independent parts adjustable toward and from each other to control the size of the flue passage similar to the passage 18 and the side walls are provided with adjustable side and end wings to adapt the attachment to installations of different sizes and contour. At the 40 same time, the equivalent of the inwardly turned flanges 21 are made adjustable to regulate their height with respect to the height of the opposed wall. The equivalent of the hood 29 is also made adjustable.

In the construction shown in Figs. 4 and 5, I 45 employ separate side portions 35 and 36. The part 35 has a wall 37 similar to the wall 19 and the part 36 has a wall 38 similar to the wall structure 20, 22. The wall 37 has an outwardly and 50 upwardly extending baffle 39 similar to the baffle 24 and the wall 38 is provided with a baffle 40 similar to the baffle 25. Adjustably supported in connection with the outer edges of the baffles 39 and 40 are longitudinal wings 41 and 42 respectively, adjustment being provided by the bolt and slot constructions represented at 43, and these wings include outwardly extending flanges 41a and 42a to take the place of the beads 24a in supporting the outer edges of the baffles 39 and 40 55 or the wings 41 and 42 in spaced relation to adjacent walls of a support. At the ends of each of the baffles 39 and 40 are adjustable end wings 44 whereby the length of said baffles may be increased and decreased, and said wings 44 are 60 provided with elongated slots 45 through which are passed bolts 46. The latter also pass through elongated slots 47 in coupling straps 48 employed to adjust the relative position of the plates 37 and 38 toward and from each other.

At 49 I have shown a downwardly extending flange forming the equivalent of the flange 23, in the construction shown in Fig. 1. The flange 49 is formed by a plate adjustable vertically on the wall 37 by means of a bolt and slot structure indicated at 50 similar to the structure at 43. This serves to regulate the height of supporting the attachment above the burner. With this construction, the supporting feet 26 are omitted and I rely upon the projecting flanges 42a to support one side of the attachment in connection with the stove by engaging the adjacent wall of the stove.

At 51, I have shown two inwardly curved plates disposed adjacent the end portions of the attachment and adjustable vertically on the wall 38 of the part 36 to regulate the height thereof with respect to the upper edge of the wall 31. A bolt and slot construction as at 52 and similar to the structure 43 is employed for this purpose. At 53 I have shown a hood which takes the place of the hood 29. This hood is made of a channeled member, the side walls of which overly the upper edges of the walls 31, 38. A bolt 54 is passed through the overlying walls and serves to adjustably support the hood 53 in the desired degree of upward inclination.

From the foregoing, it will be apparent that with the construction shown in Figs. 4 and 5 of the drawing the attachment may be adjusted to govern the spacing of the plates 37 and 38, the length and width of the baffles 39 and 40, the inclination of the hood 53, the relative position of the curved plates 51 with respect to the upper edge of the wall 37 as well as the height at which the attachment is supported above the burner or burners. When the attachment is composed of sheet metal, the baffles 24 and 25 and 39 and 40 may be bent to change the inclination thereof to compensate for slight variations in a stove structure as well as to vary the size of the passages 27 and 28. The attachment as shown in Figs. 1 and 2 of the drawing is self-supporting upon the burners, and the side edges of the baffles need not necessarily engage the adjacent walls of the fire box chamber.

The attachment may be utilized in connection with various kinds and classes of burners from a single or multiple standpoint to control and regulate the flame and products of combustion rising from the burner and direct it through the unit or apparatus in connection with which it is employed to produce greater efficiency and utility in the burner operation.

Having fully described my invention, what I claim as new and desire to secure by Letters Patent is:

1. A burner attachment of the class described comprising a body having spaced, vertically disposed central walls forming a flue passage therebetween and opening through the top and bottom of said body, said walls terminating at their lower ends in outwardly and upwardly extending baffles arranged longitudinally of the first named walls.

2. A burner attachment of the class described comprising a body having spaced, vertically disposed central walls forming a flue passage therebetween and opening through the top and bottom of said body, said walls terminating at their lower ends in outwardly and upwardly extending baffles arranged longitudinally of the first named walls, and the upper edge of one of the first named walls being arranged above the upper edge of

the other wall and being curved in the direction of the second named wall.

3. A burner attachment of the class described comprising a body having spaced, vertically disposed central walls forming a flue passage therebetween and opening through the top and bottom of said body, said walls terminating at their lower ends in outwardly and upwardly extending baffles arranged longitudinally of the first named walls, the upper edge of one of the first named walls being arranged above the upper edge of the other wall and being curved in the direction of the second named wall, and a hood portion centrally of the upper edges of the first named walls and being inclined upwardly in the direction of one end of said body.

4. A burner attachment of the class described comprising a body having spaced, vertically disposed central walls forming a flue passage therebetween and opening through the top and bottom of said body, said walls terminating at their lower ends in outwardly and upwardly extending baffles arranged longitudinally of the first named walls, the upper edge of one of the first named walls being arranged above the upper edge of the other wall and being curved in the direction of the second named wall, a hood portion centrally of the upper edges of the first named walls and being inclined upwardly in the direction of one end of said body, and one of said first named walls having at the lower end thereof a projecting flange forming a supporting member for said body.

5. A burner attachment of the class described comprising a body having spaced, vertically disposed central walls forming a flue passage therebetween and opening through the top and bottom of said body, said walls terminating at their lower ends in outwardly and upwardly extending baffles arranged longitudinally of the first named walls, the upper edge of one of the first named walls being arranged above the upper edge of the other wall and being curved in the direction of the second named wall, a hood portion centrally of the upper edges of the first named walls and being inclined upwardly in the direction of one end of said body, one of said first named walls having at the lower end thereof a projecting flange forming a supporting member for said body, and means at the free outer edges of said baffles for supporting said edges in spaced relation to adjacent walls of an apparatus in connection with which the attachment is mounted.

6. A burner attachment of the class described comprising a body having spaced, vertically disposed central walls forming a flue passage therebetween and opening through the top and bottom of said body, said walls terminating at their lower ends in outwardly and upwardly extending baffles arranged longitudinally of the first named walls, the upper edge of one of the first named walls being arranged above the upper edge of the other wall and being curved in the direction of the second named wall, a hood portion centrally of the upper edges of the first named walls and being inclined upwardly in the direction of one end of said body, one of said first named walls having at the lower end thereof a projecting flange forming a supporting member for said body, means at the free outer edges of said baffles for supporting said edges in spaced relation to adjacent walls of an apparatus in connection with which the attachment is mounted, and the free edges of said baffles having adjustable wings to vary the area of said baffles.

7. A burner attachment of the class described comprising a body having spaced, vertically disposed central walls forming a flue passage therebetween and opening through the top and bottom 5 of said body, said walls terminating at their lower ends in outwardly and upwardly extending baffles arranged longitudinally of the first named walls, the upper edge of one of the first named walls being arranged above the upper edge of 10 the other wall and being curved in the direction of the second named wall, a hood portion centrally of the upper edges of the first named walls and being inclined upwardly in the direction of one end of said body, one of said first named 15 walls having at the lower end thereof a projecting flange forming a supporting member for said body, means at the free outer edges of said baffles for supporting said edges in spaced relation to adjacent walls of an apparatus in connection 20 with which the attachment is mounted, the free edges of said baffles having adjustable wings to vary the area of said baffles, and means for adjusting the vertically disposed central walls toward and from each other.
- 25 8. A burner attachment of the class described comprising a body having spaced, vertically disposed central walls forming a flue passage therebetween and opening through the top and bottom of said body, said walls terminating at their lower ends in outwardly and upwardly extending baffles arranged longitudinally of the first named walls, the upper edge of one of the first named walls being arranged above the upper edge of 30 the other wall and being curved in the direction of the second named wall, a hood portion centrally of the upper edges of the first named walls and being inclined upwardly in the direction of one end of said body, one of said first named walls having at the lower end thereof a projecting 35 flange forming a supporting member for said body, means at the free outer edges of said baffles for supporting said edges in spaced relation to adjacent walls of an apparatus in connection with which the attachment is mounted, the free 40 edges of said baffles having adjustable wings to vary the area of said baffles, means for adjusting the vertically disposed central walls toward and from each other, and the curved upper edge of one of the first named walls being formed on independent members adjustable vertically on 45 said walls.
- 50 9. A burner attachment of the class described comprising a body having spaced, vertically disposed central walls forming a flue passage therebetween and opening through the top and bottom 55 of said body, said walls terminating at their lower ends in outwardly and upwardly extending baffles arranged longitudinally of the first named walls, and means for adjusting the first named 60 walls toward and from each other.
- 65 10. A burner attachment of the class described comprising a body having spaced vertically disposed central walls forming a flue passage therebetween and opening through the top and bottom 65 of said body, said walls terminating at their lower ends in outwardly and upwardly extending baffles arranged longitudinally of the first named walls, and the peripheral edges of said baffles including adjustable wings by means of which the 70 areas of the baffles may be varied.
- 70 11. A burner attachment of the class described comprising a body having spaced vertically disposed central walls forming a flue passage therebetween and opening through the top and bottom of said body, said walls terminating at their low- 75 er ends in outwardly and upwardly extending baffles arranged longitudinally of the first named walls, the peripheral edges of said baffles including adjustable wings by means of which the areas of the baffles may be varied, and means for adjusting the first named walls toward and from each other. 5
12. A burner attachment of the class described comprising a body having spaced vertically disposed central walls forming a flue passage there- 10 between and opening through the top and bottom of said body, said walls terminating at their lower ends in outwardly and upwardly extending baffles arranged longitudinally of the first named walls, the peripheral edges of said baffles includ- 15 ing adjustable wings by means of which the areas of the baffles may be varied, means for adjusting the first named walls toward and from each other, and one of the first named walls including vertically adjustable plates at the upper portions 20 thereof and including inwardly curved flanges at their upper ends.
13. A burner attachment of the class described comprising a body having spaced vertically dis- 25 posed central walls forming a flue passage there- between and opening through the top and bottom of said body, said walls terminating at their lower ends in outwardly and upwardly extending baffles arranged longitudinally of the first named walls, the peripheral edges of said baffles including ad- 30 justable wings by means of which the areas of the baffles may be varied, means for adjusting the first named walls toward and from each other, one of the first named walls including vertically adjustable plates at the upper portions thereof 35 and including inwardly curved flanges at their upper ends, and a baffle and supporting member adjustable vertically on one of the first named wall members and adapted to project below the lower surface of said body to space the same 40 above a suitable support.
14. A burner attachment of the class described comprising a body having spaced vertically dis- 45 posed central walls forming a flue passage there- between and opening through the top and bot- 50 tom of said body, said walls terminating at their lower ends in outwardly and upwardly extending baffles arranged longitudinally of the first named walls, the peripheral edges of said baffles includ- 55 ing adjustable wings by means of which the areas of the baffles may be varied, means for adjusting the first named walls toward and from each other, one of the first named walls including vertically adjustable plates at the upper portions thereof 60 and including inwardly curved flanges at their upper ends, a baffle and supporting member ad- 65 justable vertically on one of the first named wall members and adapted to project below the lower surface of said body to space the same above a suitable support, and other means on said baffles 70 for supporting said body in connection with ad- jacent walls. 75
15. The combination with a fuel oil burner, of an attachment for controlling and regulating the discharge of flame and products of combustion 85 from the burner, said attachment being mounted in close proximity to the upper discharge end of the burner, means centrally of the attachment for drawing the flame and products of combustion in a vertical column above the burner and to spread the same horizontally at a point above the top of the burner, said means comprising a long contracted passage at the lower end of which is an outwardly flared throat, and oppositely di- 90 rected baffles extending from the lower portion 75

of said first named means in an upwardly inclined direction and controlling the discharge of flame and products of combustion to opposite sides of the attachment and in spaced relation to said 5 vertical column.

16. The combination with a fuel oil burner, of an attachment for controlling and regulating the discharge of flame and products of combustion from the burner, said attachment being mounted 10 in close proximity to the upper discharge end of the burner, means centrally of the attachment for drawing the flame and products of combustion in a vertical column above the burner and to spread the same horizontally at a point above the top of 15 the burner, said means comprising a long contracted passage at the lower end of which is an outwardly flared throat, oppositely directed baffles extending from the lower portion of said first named means in an upwardly inclined direction 20 and controlling the discharge of flame and products of combustion to opposite sides of the attachment and in spaced relation to said vertical column, and means at the free edges of said baffles

for supporting the same in spaced relation to adjacent walls of a support to form restricted passages at such edges.

17. The combination with a burner of the class described, of a device for directing the flame and products of combustion discharged from said burner, said device having means for dividing the flame and products of combustion discharged from the burner into three distinct paths, said means comprising elongated and spaced parallel 10 walls forming a long narrow passage centrally of said device and forming a central discharge and laterally and upwardly extending baffles directing the flame and products of combustion outwardly 15 and upwardly at opposite sides of the burner and in spaced relation to said central discharge, and means at the upper end of said parallel walls and above said central discharge for deflecting the flame and products of combustion horizontally at 20 a point above the top of the burner and above the ends of said baffles.

FREDERICK C. LAHN.
